UNITED STATES PATENT OFFICE.

CHARLES HENRY FOX, OF PHILADELPHIA, PENNSYLVANIA.

DESIGN FOR A FLOWER-DISPLAY STAND.

Application filed April 15, 1924. Serial No. 9,287. Term of patent 3½ years.

To all whom it may concern:

Be it known that I, CHARLES HENRY FOX, of a flower display stand showing my new design.

a citizen of the United States, residing in Philadelphia, in the county of Philadelphia and State of Pennsylvania, have invented a new, original, and ornamental Design for a Flower-Display Stand, of which the following is a specification, reference being had to the accompanying drawing, forming part hereof.

The figure is a view in front elevation of a flower display stand showing my new design.

I claim:

The ornamental design for a flower display stand, as shown.

In testimony whereof I have hereunto signed my name this 11th day of April, A. D., 1924.

CHARLES HENRY FOX.
